UNITED STATES PATENT OFFICE.

JASON G. CRANE AND JOHN W. WOPAT, OF KANSAS CITY, MISSOURI, ASSIGNORS TO
RELIABLE ELECTRIC COMPANY, OF CHICAGO, ILLINOIS.

CABLE TERMINAL AND SUPPORT THEREFOR.

Application filed December 17, 1921. Serial No. 523,240.

Our invention relates to cable terminals and supports therefor, and more particularly to the bracket member for supporting a pole cable terminal, such as is used in telephone work, on a pole or other supporting member.

It is a purpose of the invention to provide a supporting member of the above mentioned character which is cheap in construction and which is light in weight, thus reducing the expense of shipping the same, and that is not readily broken. Ordinarily devices of this character are made of cast iron and are heavy, expensive and readily broken.

It is a purpose of the invention to provide a supporting bracket for the purpose referred to above which is made of a plurality of parts comprising a securing bracket and a sheet metal member supported by the same, said sheet metal member comprising a laterally extending portion which is adapted to act as a closure member to prevent birds or animals from entering the interior of the cable terminal.

Other objects and advantages of the invention will appear as the description of the accompanying drawings proceeds. However, we desire to have it distinctly understood that we do not intend to limit ourselves to the exact details shown in the drawings or described in the specification, but that we intend to include as part of our invention all such obvious changes and modifications of parts as would occur to a person skilled in this art and as would fall within the scope of the claims.

In the drawings:

Fig. 1 is a transverse section of the cable terminal supporting member taken substantially at the bottom of the cover member; and

Fig. 2 is a side elevation of the pole cable terminal showing the cover member partly broken away and showing the supporting member in section, said section being taken substantially on the line 2—2 of Fig. 1.

Referring in detail to the drawings, a pole cable terminal 5 is shown having a cover member or hood 6 and the usual wooden mounting block 7 upon which the fuse members 8 are mounted in any suitable manner. The member 7 is provided with a downward

extension 9 to which the supporting devices for the cable terminal are secured. These supporting devices comprise a U-shaped bracket member 10 having the parallel leg portions 11, the connecting portion 12 and the pole engaging portions 13, said pole engaging portions being provided with openings for receiving the securing devices 14 which enter the pole 15 to hold the parts in position on the pole, the openings being shown at 16 in Fig. 2. The U-shaped bracket member 10 is provided with openings for receiving the bolts 17 for securing the bracket 10 to the block 9. Mounted on the bracket 10 and having downwardly extending portions or flanges 18 extending between the U-shaped member 10 and the downward extension 9 of the supporting block 7 is the sheet metal member 19, said sheet metal member 19 being provided with a laterally extending flange portion having a circular outline, said flange portion comprising wings 20 extending to each side of the members 11 and a portion 21 which extends between the portions 11.

It will also be noted that the portions 20 and 21 of the member 19 will form substantially a complete closure for the pole cable terminal when the cover member 6 is in place, the only opening being that for the pole 15 and the extension 9 of the block 7, which opening will be substantially closed due to the fact that the cable will enter through the same and that the wires from the cable will spread or fan out from this cable so as to prevent entrance of animals through this opening when the cover member is in place, it being noted that the lower edge portion 22 of the cover 6 extends below the flange portion 19. The cover member, it will be noted, is cut away at 23 so that the same will embrace the legs 11 of the U-shaped bracket member. The lower edge 24 of the cover member at the cut away portion rests on the members 11, thus preventing forward movement of the cover member relative to the support. A chain 25 is provided which is secured to the cover member at 26 and to the member 11 at 27 for securing the cover member to the support, said chain permitting the lifting of the cover member off of the support, so as to permit of ready access to the interior of the pole

cable terminal member. The bolts 17 hold the parts of the supporting device together, and also secure the wooden supporting block of the pole cable terminal in place on the support.

Having thus described our invention, what we desire to claim and secure by U. S. Letters Patent is:

1. In a device of the character described, 10 a bracket member having a bight portion and a pair of substantially parallel arms terminating in pole engaging ends, a terminal block secured between the arms of said bracket member, and a housing for said block comprising a bottom closure member mounted on said bracket member and a cover member having its bottom edge extending below said bottom closure member, said cover member engaging the arms of 15 said bracket and the peripheral edge of said closure member to hold said cover in position.
2. In a device of the character described, 20 a bracket member having a bight portion and a pair of arms terminating in pole engaging ends, a terminal block secured between the arms of said bracket member, and a housing for said block comprising a bottom closure member mounted on said bracket member and a cover member having its bottom edge extending below said bottom closure member, 25 said cover member engaging the arms of said bracket and the peripheral edge of said closure member to hold said cover in position, said bracket having a curved portion connecting said arms with which said cover engages.
3. In a device of the character described, 30 a bracket member having a pair of arms terminating in pole engaging ends, a terminal block mounted between the arms of said bracket member, and a housing for said block comprising a bottom closure member mounted on said bracket member and a cover member having its bottom edge extending below said bottom closure member, said cover member engaging the arms of said bracket and the peripheral edge of said closure member to hold said cover in position, 35 said cover member having a notch the edge of which is engaged by said arms to limit downward movement of said cover.
4. In a device of the character described, 40 a bracket member having a pair of arms terminating in pole engaging ends, a terminal block mounted between the arms of said bracket member, and a housing for said block comprising a flanged bottom closure member mounted on said bracket member, 45 the flanges of said closure member extending between said block and said arms, and a cover member having its bottom edge extending below said bottom closure member, said cover member engaging the arms of said bracket and the peripheral edge of said closure member to hold said cover in position.
5. In a device of the character described, 50 a U-shaped strap metal bracket member having a pair of arms terminating in pole

engaging ends, a terminal block mounted 5 between the arms of said bracket member, and a housing for said block comprising a bottom closure member mounted on said bracket member having a curved edge wing portion and depending flanges extending between said arms, and a cover member having its bottom edge extending below said bottom closure member, said cover member engaging the arms of said bracket and the peripheral edge of said closure member to hold said cover in position.

6. In a device of the character described, 6 a bracket member having a pair of arms terminating in pole engaging ends, a terminal block mounted between the arms of said bracket member, and a housing for said block comprising a bottom closure member mounted on said bracket member and a cover member having its bottom edge extending below said bottom closure member, 7 said cover member engaging the arms of said bracket and the peripheral edge of said closure member to hold said cover in position, said bracket having a curved portion connecting said arms with which said cover engages.

7. A device of the character described, 8 comprising a bracket member having a pair of parallel legs, a terminal supporting block mounted between the legs of said bracket, a cover member and a closure member mounted on said bracket and extending outwardly therefrom.

8. A device of the character described, 9 comprising a bracket member having a pair of parallel legs, a terminal supporting block mounted between the legs of said bracket, a cover member and a closure member mounted on said bracket and extending outwardly therefrom on opposite sides of said legs.

10. A device of the character described, comprising a bracket member having a pair of parallel legs, a terminal supporting block mounted between the legs of said bracket, a cover member and a closure member mounted on said bracket, and extending outwardly therefrom, said cover extending down over said bracket.

In witness whereof, we hereunto subscribe our names this 9th day of December A. D., 1921.

JASON G. CRANE.
JOHN W. WOPAT.
